UNITED STATES PATENT OFFICE.

HENRY T. MOODY, OF NEWBURYPORT, MASSACHUSETTS, ASSIGNOR TO THE VICTOR MANUFACTURING COMPANY, OF SAME PLACE.

RAIL-SUPPORT.

SPECIFICATION forming part of Letters Patent No. 408,892, dated August 13, 1889.

Application filed January 31, 1889, Serial No. 298,303. (No model.)

To all whom it may concern:

Be it known that I, HENRY T. MOODY, of Newburyport, in the county of Essex and State of Massachusetts, a citizen of the United States, have invented a new and useful Improvement in Rail-Supports, of which the following is a full, clear, and exact description, reference being had to the accompanying drawings, forming a part of this specification, 10 in explaining its nature.

The invention relates to a rail-support for door-hangers, trucks, parcel-carriers, and similar appliances, comprising two sheet-metal brackets or arms formed from flat plate by 15 bending or striking up, one of which has an ear by which it is secured in place, a horizontal arm, and an upwardly-extended end, the other of which has an ear by which it is secured in place, and a downwardly-extended 20 arm, and a bearing end or section parallel with the upturned end of the first part or section of the support, and separated therefrom by the thickness of the rail, the said upturned end, bearing-section, and rail preferably being secured together by a bolt and nut or 25 rivet. A rail-support of this construction combines simplicity and cheapness of manufacture with great stiffness and durability. It acts to stay the rail from moving laterally 30 in either direction, and is easily applied to the rail and fastened in place.

In the drawings, Figure 1 is a view in front elevation representing the abutting ends of two rails and the rail-supports. Fig. 2 is a 35 view in section upon the dotted line of Fig. 1. Figs. 3, 4, 5, and 6 represent slight variations or details, to which reference will hereinafter be made. Fig. 7 is a view in plan of the construction represented in Fig. 2, showing a narrow upper section and a wide lower section. Fig. 8 is a view in elevation, reduced in size 40 as compared with Fig. 7, showing both the upper and lower sections as made wide.

A represents one rail and A' the following 45 or next rail in order.

a a' represent, respectively, their abutting or contiguous ends.

B represents the lower member of the rail-support, and C the upper member. Both 50 members are made from metal strips cut from

flat metal plate by bending or striking up. The lower section B is thus formed with an ear b, in which is formed a screw-hole b², by which it is fastened or secured to the studding or support to which the rail is attached. It has the extension b³ from its upper end and the turned-up end b⁴, which I have termed a "face-plate," in which is formed a screw or bolt hole b⁵. The upper member C of the rail-support has 60 the ear c, in which is formed the screw-hole c² to receive the screw c², by which it is fastened to the studding or wall. From the lower end of this ear the support is bent downwardly and outwardly to form the arm or extension c³, and the end c⁴ of the support is bent at an obtuse angle to the arm c³ to bring its face parallel with the turned-up end b⁴ of the lower section, but separated therefrom by a space sufficient to receive the thickness of 70 a rail. This end c⁴, I call an "extension" or "bearing" plate. The sections B C of the rail-support as thus made are fastened to the studding or wall and the rail placed between their ends, as represented in Figs. 2 and 3, 75 and the rails secured together by riveting or by a bolt and nut.

In Fig. 1 I have represented the section B of the rail-support made wider where the ends of the rails abut, in order that it may act 80 additionally as a binding-plate to fasten the ends of the rails together at that point and maintain them in line, and when it is so used the face-plate b⁴ has two bolt, screw, or rivet holes, and the end of one rail is secured 85 by a rivet or bolt between the extension or bearing plate c⁴ and one end of the face-plate b⁴, and the end of the next rail in order is riveted or attached directly to the face-plate b⁴. Of course, if desired, the upper section C 90 may be as wide as the lower section B, in which case the extension or bearing plate c⁴ would act as a binding or clamping plate in addition to the plate b⁴, as represented in Fig. 8; but I prefer the first form of construction. 95

In Fig. 4 I have represented the support, where used at the meeting-point of two rails, as made in three parts—namely, a wide lower section B and two narrow upper sections C.

In Fig. 5 I have represented the abutting 100

ends of two rails as secured by separate supports, each of which comprises a single lower and upper section, the two supports being placed closely together.

5 In Fig. 6 I have represented the lower sections of the support out of line with the upper sections. This construction requires the use of an additional bolt and nut, screw, or rivet to that shown in Figs. 1 and 2.

10 The invention may be used for a support for rails to carry door-hangers, trucks, or rolls of any kind. It will be observed that each section of the support is so shaped that the screw by which it is secured in place is 15 always accessible after the rail is in position; also, that the under section acts to prevent the rail from moving laterally outwardly, the upper section from being moved laterally inward, and that both sections act as a very 20 effective and rigid brace or stay, complementing and co-operating with each other.

I prefer to attach the rails to the upper and lower sections of the supports by rivets, and to so attach the supports to the rails before 25 they are shipped from the factory, in order that the rails may be secured in place by simply screwing the supports to a stringer, wall, or other holding device. It will be seen that by this construction of rail-support the 30 strain is removed from the rivets and taken directly by the plates b^4 c^4 of the supports, and that these plates are so placed and stayed that they act to prevent the track or rails from twisting by any straining or irregular 35 action of the hanger-rolls upon them.

Having thus fully described my invention, I claim and desire to secure by Letters Patent of the United States—

1. A rail-support comprising the under section B, having the perforated ear b , arm b^3 , 40 perforated face-plate b^4 , and the upper section C, having the perforated ear c , the arm c^3 , and the extension or bearing plate c^4 , the said face-plate b^4 being adapted to extend upon the outside of the rail and the bearing- 45 plate c^4 upon the inside of the rail, substantially as described.

2. The combination, in a support for a hanger or other rail, of the section C, having the perforated ear c , the arm c^3 , and the bearing-plate c^4 , the section B, having the perforated ear b , the arm b^3 , the face-plate b^4 , wider than the bearing-plate c^4 , and having two rivet or bolt holes, and the rails A A', the end of one of which is fastened directly 50 to the face-plate b^4 , and the end of the other of which is fastened to the face-plate b^4 and bearing-plate c^4 , substantially as described.

3. In a rail-support, in combination with the rail, a bracket or hanger in two sections 60 having means by which they are adapted to be secured to a stringer or wall, one of which sections has the inner bearing-plate or extension c^4 , the other of which has the outer face-plate or extension b^4 , and the two being 65 separated from each other by a space of the thickness of the rail, to which it is secured by a rivet, bolt, or screw passing through the plates b^4 c^4 , and the rail, substantially as described.

HENRY T. MOODY.
